SORTING MECHANISM

William W. Lasker, Brooklyn, N. Y., assignor to
Remington Rand Inc., Buffalo, N. Y., a corpora-
tion of Delaware

Application July 30, 1936, Serial No. 93,366

4 Claims. (Cl. 209—110)

This invention relates to record card sorting machines and particularly to improvements therein which have for their purpose the segregating of all cards which are duplicates of the 5 respective preceding cards.

A device such as that of the present invention is particularly useful in checking cards which are to be used for the preparation of pay rolls and segregating those which are duplicates of 10 their immediate predecessors. It has been found in the field that men have been able to cause the inclusion in a pack of pay roll cards of a second or even a third card showing money due them. If these cards were allowed to pass 15 through the tabulator, fraudulent entries in the pay roll would result. By means of visual inspection these entries could be located and appropriate corrections made. Such a process would not, however, be guaranteed to be absolutely free from errors due to the human element. 20

The system involving the present invention contemplates the arrangement of all cards pertaining to a single pay roll in the sequential order of the employee's identification numbers. 25 Thus, all the cards having the same identification numbers would be collected together and would occur in the pack sequentially. Those cards which differ from each other as regards employee's identification number are considered 30 to be acceptable, while of those which are alike in their identification, one is acceptable and the others are not acceptable.

In this invention, the mechanism of Patent 2,044,119, issued June 16, 1936, to William W. 35 Lasker is adapted to control mechanism which will cause the separation of the cards in a pack into two groups, namely, those which are acceptable and those which are not acceptable.

Accordingly, the first object of this invention 40 is to provide means to prevent the inclusion of non-acceptable cards in a group of cards.

Another object is to provide means to separate consecutive cards having common designatory matter.

45 A further object is to provide means to cause all cards having differing designatory data to be segregated from all cards having identical designatory data.

A still further object is to provide mechanism 50 for separating from a sequentially arranged group of cards any card which is a duplicate of its respective predecessor.

The present invention contemplates the combination of record sensing means, change-of- 55 designation determining means, card transport-

ing means, card guiding means, and means responsive to said change-of-designation determining means for controlling the action of said card guiding means.

Other objects and structural details will be 5 apparent from the following description, when read in connection with the accompanying drawings wherein:

Figs. 1 and 1A together show a side elevation of the machine in stopped position with sensing 10 chamber empty;

Fig. 2 is a diagrammatic isometric view showing the card control mechanism;

Figs. 3 and 3A together show a sectional side 15 elevation taken on the line 3—3 of Fig. 4;

Figs. 4 and 4A together show an elevation of the mechanism as seen from the rear of the machine, the left in Fig. 1;

Fig. 5 is an exploded isometric view of certain 20 of the essential instrumentalities common to the reference patent and the present invention.

The basic structure

In the cited Lasker Patent 2,044,119, the well known Powers tabulator is shown in the form in 25 which it has been in public use for a number of years. This machine is capable of feeding perforated cards from a storage magazine to a sensing device which seeks out the perforations and causes the data thus portrayed to be transmitted to an adding mechanism. Also there is shown therein, a device for sensing a change-of- 30 designation and mechanism for causing this change to initiate a total. Since the operation of the mechanism in the present invention depends upon the change-of-designation sensing device, a brief summary of the structure and operation of the mechanism of the above cited application will now be given. For convenience, 35 elements which are common to this application and to the cited patent will bear the reference numerals of the latter. Certain other elements which are part of the structure of the reference patent, but which are only incidental to the present invention are illustrated, but not described, for the purpose of showing the general construction of the machine.

In Figs. 1 and 1A hereof (Figs. 1, 5, 10, 20, 21 and 22 of the reference), are shown mechanisms, 50 respectively, for feeding cards from the storage magazine, for transporting the cards through the machine, for stopping the card while the perforations are being utilized for setting the machine in accordance therewith, for releasing the 55

previous settings, and for storing the cards after they have served their purpose.

Card feeding

5 A shaft 25 (Fig. 1) carries cam 268 (Fig. 5 also Fig. 22 of the reference) which coacts with follower 267 to cause it to oscillate arm 265 about pivot 266 and by reason of connecting link 264 oscillate arm 263 and shaft 22 of the card feeding mechanism, which shaft is journaled in frame 15 (Fig. 1). A spring 270 tensioned between arm 263 and a suitable anchor in frame 15 tends to maintain follower 267 against cam 268. Fixed to shaft 22 is an upwardly extending arm 15 21 (Fig. 1 of the reference, Fig. 3A hereof) at the upper end of which is pivoted one end of picker link 20. The other, or forward end of link 20 is pivoted to block 18 of the picker mechanism. If shaft 25 be caused to rotate, the high portion of cam 268 will cause arm 265, and the chain of mechanism operatively connected thereto by link 264 to be actuated to move picker block 18 rearwardly and feed a card toward the transporting rolls. Journaled also in frame 15 20 are the shafts 90, 91, 104 and 105 of the card transporting rolls.

Card stop

30 Fixedly mounted on shaft 25 is cam 262 (Fig. 5 hereof and Fig. 21 of the reference). This cam operates upon its follower 261 to rock arm 251 and pull link 255 downwardly against the tension of springs 244 on the member 240 and thereby rock arm 254 and shaft 252. Fixedly mounted on shaft 252 is arm 251, which pivotally supports the upper end of link 250. The lower end of this link is pivoted to lever 247 fixed on a rockable shaft 245. Lever 247 engages a recess 248 in member 240 which supports card stop 236. Rotation of shaft 25 will turn the high portion of cam 262 so that link 255 is pulled downwardly, rocking shaft 252 and the connected mechanism, thereby forcing member 240 and card stop 236 downwardly and closing the card passage.

Card sensing

50 The sensing device of the cited Patent 2,044,-119, comprises a frame 166 (Fig. 3A) within which are assembled pins 174 which are urged upwardly by springs 175. Pins 174 are arranged in columns, each column having a locking slide 190 adjacent thereto. Each slide 190 is provided with a slot and a locking tooth 188 corresponding to each adjacent pin 174. An extrusion 186 55 on each pin cooperates with a tooth 188 to lock any pins which are elevated. Frame 166 is supported on a pair of eccentric and strap assemblies 183 and is guided for reciprocation by cylindrical guides 176 working upon posts 177 (Fig. 3). 60 When shaft 25 turns, the eccentricity of the center member of assemblies 183 which are mounted thereon, causes frame 166 and its contained mechanism to be elevated. Above the frame 166 is a sensing chamber comprising two 65 matched perforated plates 135 and 136, so arranged that pins 174, the perforations in the plates and possible perforations in cards which may rest between the plates are in exact register.

Data retaining

70 Above the sensing device is a fixed assembly of pins 158 (Figs. 3, 3A, and 5) urged downwardly by springs 160. The pins of this assembly are arranged to register with the pins 174 of the reciprocating assembly. Each pin 158 is provided

with a lower extrusion 163 and an upper extrusion 322. Half of the pins 158 in a column are assembled with their extrusions 163 and 322 extending to the right, as viewed from the front of the machine, while the other half have their extrusions extending to the left. A pair of locking slides 161 is provided for each column of pins 158. These slides are adapted so that locking teeth 164 engage the respective right and left extrusions 163 when pins 158 are raised. A pair of change-of-designation slides 321 is also provided for each column of pins. These are so arranged that a cam 323 cooperates with each extrusion 322 to actuate slides 321.

5 15 Cam 52 (Fig. 20 of the reference and Fig. 1 hereof) is also fixedly mounted on shaft 25 and coacts with arm 55 to elevate rod 57 to rock arm 1614 and shaft 1613. Fixed to shaft 1613 is a pair of arms 1612 (Figs. 3 and 5 hereof) which support a bail 1611 against which locking slides 161 20 are urged by springs 154. When shaft 25 is rotated, the high portion of cam 52 will cause arm 55 to rock and elevate rod 57, which contacts the bottom of arm 1614 causing it, shaft 1613 and arms 1612 to rock counter clockwise. This rocking of shaft 1613 and arms 1612 forces bail 1611 and locking slides 161 to the right. Thus pins 158 are released and thereby conditioned to accept the reading of the next card.

Control by change-of-designation

30

To the right of slide 321 in Fig. 3A (Fig. 10 of the reference patent) is a bail 338 supported by arms 337 which are fast on shaft 336. A manually settable interponent 335 is provided. If 35 this interponent is lowered, thus filling the gap between the end of slide 321 and bail 338, displacement of the slide will cause bail 338, arm 337 and shaft 336 to rock and thereby actuate whatever instrumentalities are connected thereto. 40

Operation of basic structure

When a card enters the sensing chamber it comes to rest against the set card stop 236, the reciprocating frame 166 rises and the pins 174 45 enter perforations in plate 136. If any of these pins 174 find perforations in the card they will pass therethrough as frame 166 continues to rise; the pins 174 which do not find perforations being held back by the obstruction afforded by the 50 unperforated portion of the card. Further rise of frame 166 causes the pins which have found perforations in the card to pass through the holes in the upper plate 135. Journaled in brackets 190 on frame 166 is shaft 195 and fixed thereon 55 are arms 194 and 197. A spring coiled around shaft 195 and suitably anchored, urges this shaft in a clockwise direction. Rod 193 passes through arms 194 and one end of the links 192, the opposite end of these links being operatively connected to slides 190 by rod 191. At about the time that the raised pins 174 have passed through the hole in the card, the follower 198 on arm 197 has been raised enough to clear fixed cam 268, whereupon the spring on shaft 195 urges the associated mechanism to cause the engagement of teeth 188 with the extrusions 186 on the pins 174 which are elevated. Thus the record is locked in the sensing device.

As frame 166 continues to rise, carrying pins 70 174 which are locked with it, they will contact certain ones of pins 158 and will cause these to be raised until the locking teeth 164 in the slots of slide 161 snap under extrusions 163. Thus, the record is locked in the upper pin box. As 75

the pins 158 rise, the upper extrusions 322 thereon wipe against the faces of the cams 323 on the sides of the slots in slides 321 and thus displace these slides.

5 Provision is made, in the present machine, to prevent locking of all the pins 174 by slides 190, at times when there is no card in the sensing chamber. A no-card pin, indicated at 204 (Fig. 3) and shown in full in Fig. 10 of the Patent 10 2,044,119, to W. W. Lasker, is slidably mounted in the frame plates of the reciprocatory sensing head, and is pivotally attached to one end of a lever 207, which lever is centrally pivoted at 208 upon a bracket 210. Bracket 210 is fastened 15 to a part of the reciprocatory sensing head. The other end of lever 207 (or that end which extends toward the rear of the machine) is bent off into a lug 211, as is shown in Fig. 3. The pin 204 is urged upward by a light spring (not shown).

20 From the foregoing, it is understood that when the reciprocatory sensing head rises and no card is in the sensing chamber, the lever 207 will remain in the position shown, and ear 211 will block lever 197, thus maintaining lever 197 in its 25 retracted position. This holds the locking slides 190 ineffective. When, however, there is a card in the sensing chamber and the reciprocatory sensing head rises, the pin 204 contacts the card and is depressed, thereby, thus moving lever 207 30 clockwise. This lifts the lug 211 out of the path of lever 197, and permits locking slides 190 to lock those sensing pins which have found holes in the card.

The timed relation between eccentric 183 and 35 cam 52 is such that the unlocking of slides 161 by the action of the cam occurs when frame 166 is sufficiently close to the top of its travel that if two successive cards bear the same indicia, either in whole or in part, slides 161 will relock 40 those pins 158 which are associated with the unchanged indicia. Hence, these pins 158 are not permitted to descend and the associated slide 321 is not displaced. But if the indicia does 45 change, pins 158 will descend since there is no pin 174 to hold them up, and slides 321 will be displaced. Such an event is termed a change-of-designation.

The mechanism of the invention

50 In the present problem it is desired that when the designatory matter changes card by card, the cards will be deposited in one of two receptacles, but if the designatory matter does not change, that is, if two successive cards bear the same 55 serial number, the second, or duplicate, will be deposited in the other receptacle. Advantage is taken of the motion of the change-of-designation slide 321 to secure the desired result.

Card guiding mechanism

60 Mechanism is provided for guiding the cards into the proper receptacle. This mechanism comprises shutter 401 (Figs. 1 and 2), shaft 402, arms 404 and 405, ear 406, link 407, arm 408, follower 410, spring 411, cam 414, plate 416 (Figs. 3A and 4) and screw 417. Shutter 401 is fixedly mounted on shaft 402, which is journaled in suitable brackets 403 (Figs. 4 and 4A). Fixed to shaft 402 are two arms, respectively, 404 and 405. Arm 404 is substantially horizontal and extends rearwardly terminating in ear 406. Arm 405 extends downwardly and its lower end pivotally supports the rearward end of link 407. Arm 408 pivoted at 70 409 in plate 416 supports the forward end of link 407 and also follower 410. Spring 411 is

anchored at one end to stud 412 in link 407 and at the other end to anchor 413. Spring 411 urges follower 410 against cam 414 which is fixedly mounted on shaft 25. Plate 416 is secured to frame 15 by suitable fastenings and is provided with a tapped hole for receiving a shouldered screw 417 (Figs. 2 and 3A). This screw is disposed in a hole in arm 408 and provides means for limiting the oscillatory motion of this arm and for preventing its lateral displacement. As shaft 25 turns the high spot 415 on cam 414 urges follower 410 and arm 408 clockwise, as seen in Fig. 3A, about pivot 409 to pull link 407 and rock shaft 402 and shutter 401 counter clockwise. This motion forces ear 406 downwardly into position for latching, as will now appear.

Latching mechanism

Mechanism comprising arm 421, link 422, latch 20 423 and spring 425 is provided for latching the above described mechanism. Arm 421 is fixedly mounted on shaft 336 and pivotally supports a rearwardly (leftwardly in Fig. 1) extending link 422, the rearward end of which is pivotally supported by latch 423 which is pivoted at 424. 25 Latch 423 is urged to latching position by a spring 425. Whenever, then, a change in the serial number of the card, that is, the designatory matter, occurs, slide 321 is displaced, as has been described above, and shaft 336 is rocked. Thus, arm 421 is moved counter clockwise, link 422 is pulled and latch 423 is removed from its effective position which is in engagement with ear 406. Spring 425 is of strength sufficient to cause the return of slides 321 to the position where they will be influenced by the next succeeding motion of a pin 158.

Card receptacles

A receptacle 431 is provided for the so-called "accepted" cards and another receptacle 432 is provided for the rejected cards.

Rejected card receptacle 432 is provided with gates 435 which are hinged at 436 and are urged to closed position against stops 437 by springs 438. Thus, the rejected cards may be removed from their receptacle 432 as desired by first removing the cards from receptacle 431 and then pulling the other cards out through that receptacle. Gates 435 will yield to the pressure put on them in withdrawing the rejected cards and will return to closed position under the action of springs 438 as soon as the cards are clear of the gates.

Card conveying

Mechanism is provided for conveying cards destined for receptacle 431. This mechanism consists of sprocket wheels 441 (Fig. 4A) and 60 442, shaft 443, chain 444, rolls 445, and 446, 65 shaft 448, arms 449 and springs 450. Sprocket wheel 441 is fixed to feed roll shaft 104 and sprocket wheel 442 is fixedly mounted on shaft 443 which is journaled in brackets 403, while chain 444 is continuous and envelops both sprocket wheels. Rolls 445 are fixed on shaft 443 and coact with spring urged rolls 446 to convey the passing cards. Rolls 446 are mounted on shaft 448 which is journaled in arms 449. 70 Arms 449 are pivoted respectively on pins 452 in brackets 403 and are spring urged clockwise, as viewed in Fig. 3, by springs 450. Bail 451 (Figs. 3 and 4) journaled on pins 452 supports a pair of guide fingers 453 which prevent cards being 75

thrown beyond the confine of receptacle 431 by the action of rolls 445, 446.

Summary of operations

In the commercial adaptation of the mechanism of the present invention certain preliminary operations are necessary. Cards each bearing a perforated record of an employee's serial number, or other designatory data, must be prepared. This may be done by any of the well known methods and, therefore, need have no further consideration in this disclosure. The cards are then sorted to arrange them in the sequential order of the above mentioned designatory data. This presumably will be done by a sorting machine of the general character of the well known Powers sorting machine, which has been in public use for many years. Such a machine will arrange the cards in sequential order with duplicates, if any, next to each other. The machine of the present invention may then be utilized to segregate those cards which are duplicates. To that end, the cards are placed in the card magazine and interponents 335 corresponding to the card columns in which the designatory data appears are set in effective position by the manipulation of members 321.

Let it be assumed that card picker 18 has been actuated by the rotation of shaft 25 and has moved a card from the magazine toward the sensing chamber into which the feed rolls associated with shafts 93 and 94 have propelled it until it came to rest against card stop 236 which has, because of the rotation of shaft 25, been set in effective position. As the sensing mechanism is raised, under the influence of and because of the rotation of shaft 25, certain pins 174 will find perforations in the card, while the remaining pins will be depressed because of the restraining action of the unperforated portions of the card. At about the time when pins 174 have passed through such holes as exist, arm 196, which moves as a part of the sensing mechanism, has been raised so that its follower 198 is clear of fixed cam 200. A suitably situated spring then causes teeth 183 in slides 190 to engage extrusions 185 in the sides of those pins 174 which are elevated.

As those pins 174 which are locked continue to rise with the rising sensing mechanism assembly, they contact the bottom ends of certain pins 158 and elevate them to a position such that their extrusions 163 are locked by teeth 164 in the slots of slides 161 and their extrusions 322 are at the top of the slots in slides 321.

As extrusions 322 on the pins associated with the columns in which the designatory data occurs move upwardly, they wipe the faces of the cams 323 in the slots in slides 321 and, because interponent 335 is in effective position, bail 338, shaft 336 and shutter 401 are rocked to swing latch 423 clockwise and thus release ear 406. Spring 411 then acts to swing shutter 401 clockwise and the card is propelled by rolls 445 and 446 into receptacle 431. Shortly thereafter the high spot 415 on cam 414 contacts follower 410 and the mechanism associated therewith is actuated to rock shaft 402, shutter 401 and arm 404. This motion positions shutter 401 to guide a card into reject receptacle 432 and simultaneously swings ear 406 downwardly until it is engaged by latch 423, thereby locking shutter 401 in card rejecting position.

If the designatory data of the second card is a duplicate of that of the first card, slide 161 will 75 re-lock the elevated pins 158 before they have an

opportunity to descend. Hence, there will be no motion of the change-of-designation slide and no consequent release of shutter 401. Therefore, the duplicate card will be conveyed to the reject receptacle 432.

If the designatory data of the third card is different from that of its predecessor, the extrusions 322 on the elevated pins 158 will wipe the surfaces of the cams 323 in the slots of the associated slides 321 when these pins 158 descend after being released by slide 161. The wiping of the cams by extrusions 322 will cause a lateral motion of slides 321 and the actuation of the associated mechanism in the same manner as when the first card passed through the machine. Therefore, 15 this card is passed into the receptacle 431 which contains the accepted cards.

As the cards continue to be fed, the mechanism operates according to the description for handling the first and third cards or according to 20 that for handling the second card, depending upon whether two successive cards are duplicates or not.

While I have described what I consider to be a highly desirable embodiment of my invention, 25 it is obvious that many changes in form could be made without departing from the spirit of my invention, and I, therefore, do not limit myself to the exact form herein shown and described, nor to anything less than the whole of my invention as hereinbefore set forth, and as herein-after claimed.

What I claim as new, and desire to secure by Letters Patent, is:

1. In a machine of the class described, the 35 combination of sensing means for sensing a designating field of a punched card and capable of sensing a variety of different designation hole-patterns, means for receiving said hole-pattern sensing and retaining it for one machine cycle, 40 means for detecting differences in pattern between successive cards fed to said sensing means, means for feeding cards to said sensing means and thence to one and the other of two receiving stations, a deflecting device normally latched in 45 position to guide cards to one of said receiving stations and urged to a position to guide them to the other of said stations, and means operable by said difference detecting means upon a lack of correspondence in the designation patterns of two 50 successive cards to unlatch said deflecting device.

2. In a machine of the class described, the 55 combination of sensing means for sensing a designating field of a punched card and capable of sensing a variety of different designation hole-patterns, a pattern-retaining device settable by said sensing means, means acting at every machine cycle to release the retained set-up in said retaining device to erase the pattern set therein, means for detecting differences in pattern between successive cards fed to said sensing means, 60 means for feeding cards to said sensing means and thence to one and the other of two receiving stations; a deflecting device normally latched in position to guide cards to one of said receiving 65 stations and urged to a position to guide them to the other of said stations, and means operable by said difference detecting means upon a lack of correspondence in the designation patterns of two successive cards to unlatch said deflecting 70 device.

3. In a machine of the class described, the combination of sensing means for sensing a designating field of a punched card and capable of sensing a variety of different designation hole- 75

- patterns, means for receiving said hole-pattern sensing and retaining it for one machine cycle, means for detecting differences in pattern between successive cards fed to said sensing means, 5 means for feeding cards to said sensing means and thence to one and the other of two receiving stations, a deflecting device normally latched in position to guide cards to one of said receiving stations and urged to a position to guide them to the other of said stations, means operable by 10 said difference detecting means upon a lack of correspondence in the designation patterns of two successive cards to unlatch said deflecting device, and machine operated means for restoring said deflector to its normal position.
- 10 4. In a machine of the class described, the combination of sensing means for sensing a designating field of a punched card and capable of sensing a variety of different designation hole-
- patterns, a pattern-retaining device settable by said sensing means, means acting at every machine cycle to release the retained set-up in said retaining device to erase the pattern set therein, means for detecting differences in pattern between succeeding cards fed to said sensing means, means for feeding cards to said sensing means and thence to one and the other of two receiving stations, a deflecting device normally latched in position to guide cards to one of said receiving 10 stations and urged to a position to guide them to the other of said stations, means operable by said difference detecting means upon a lack of correspondence in the designation patterns of two successive cards to unlatch said deflecting device, and 15 machine operated means for relatching said deflector.

WILLIAM W. LASKER.
